COVERED EXPANSION JOINT

Richard T. Lyons, Toronto, Ontario, Canada, assignor to The Patent and Licensing Corporation, New York, N. Y., a corporation of Massachusetts

Application November 24, 1948, Serial No. 61,888

3 Claims. (Cl. 72—106)

1

This invention relates to a device for covering the vertical faces of expansion joints in masonry constructions. This invention is primarily concerned with a device for covering the vertical faces of expansion joints containing heat-liquefiable rubberized bituminous sealing compositions.

In the construction of large concrete structures, such as athletic stadia and the like, the concrete portions of the structures are formed in sections and joints between adjacent sections are provided to accommodate the expansion and contraction of the concrete under the atmospheric conditions encountered in service. These joints are filled with an adhesive, elastic sealing compound which is supported by a metal water-stop or the like positioned in the joint below the surface of the exposed portion of the structure. Rubberized bituminous compositions which may be liquefied at elevated temperatures of the order of 400° to 500° F., and poured into the joint are particularly suitable for this purpose. A problem arises, however, in connection with the vertical face of expansion joints in which such sealing compositions are employed as, for example, in the vertical riser sections of stadium terraces. When the liquefied sealing material is poured into the joint there is a tendency for it to run out along the vertical face of the joint before the material has had time to solidify. Further, sealing compositions employed for this purpose exhibit cold flow and, during periods of expansion when the space between adjacent concrete sections is narrowed, the sealing material tends to be forced out of the vertical face of the joint and becomes displaced, making the joint unsightly and sometimes causing permanent injury to the bond between the composition and the concrete.

It is an object of the invention to provide a device which will afford lateral support for the sealing composition in vertical faces of expansion joints.

It is a further object of the invention to provide a device of the character indicated which will be suitable for permanent installation across the vertical face of an expansion joint and which will prevent objectionable displacement of the sealing composition during periods of expansion.

According to the invention, I provide a device having a body, with a substantially flat outer surface, and arm-like extensions which, when the body is placed across the vertical face of an expansion joint, extend into the joint and become firmly embedded in the sealing composition subsequently poured into the joint and allowed to cool. My device provides a permanent lateral

2

support for the sealing composition in the expansion joint while permitting free expansion and contraction of the joint.

Other objects and features of the invention will be apparent from the detailed description which follows, and from the drawing, in which—

Fig. 1 is a perspective view of an embodiment of the invention suitable for the vertical faces of expansion joints in step-like constructions;

10 Fig. 2 is a perspective view of a modified form of the device of the invention adapted for use with the lowermost vertical face of an expansion joint in step-like constructions;

15 Fig. 3 is a diagrammatic view of a concrete stepped construction showing the use of the embodiments of the device illustrated in Fig. 1 and Fig. 2;

Fig. 4 is a sectional view along the line 4—4 of Fig. 3;

20 Fig. 5 is an embodiment of the invention particularly adapted for use in covering expansion joints having long vertical faces;

Fig. 6 shows the use of the embodiment of the invention illustrated in Fig. 5; and

25 Fig. 7 is a sectional view taken along the line 7—7 of Fig. 6.

Referring to the drawings, and particularly to Fig. 1, the numeral 10 designates the body of one embodiment of my joint covering device which is adapted for use in the construction of stepped structures. A leg 11, narrower than the body 10, extends downwardly from the lower edge of the body 10, and an arm 13 extends rearwardly from the upper portion of the body 10 adjacent its upper edge. Arm 13 is relatively narrow compared with the body 10 and is provided with a flanged end 16. It will be observed that the arm 13 is formed in such manner that it is joined to the body 10 somewhat inwardly of the upper edge thereof, thereby forming two wings 14 and

30 35 40 45 50 55 15. In this form of the device the body 10 is adapted to extend across the vertical face of an expansion joint of a step riser section, the leg portion 11 is adapted to extend downwardly into the subjacent horizontal face of the joint and the arm 13 is adapted to be bent so that it forms an angle with the body portion of say about 75° and to extend obliquely into the joint.

Referring particularly to Fig. 2 an embodiment of the invention is shown which is particularly adapted to cover the face of the expansion joint in the lowermost riser section of a stepped construction. In this form the device comprises a body portion 20, an arm portion 21 extending outwardly from the body 20 adjacent the upper

edge thereof, and an arm portion 22 extending from the lower end of the body 20. Arm portions 21 and 22 are provided with flanged ends 24 and 25 respectively.

In Fig. 5 is shown an embodiment of my invention, designated generally by the numeral 30, adapted for use in covering expansion joints having relatively long vertical faces as are formed, for example, in the construction of walls, dams and the like.

The body portion has a T-shaped cross section and comprises side sections 33 and 34 and a center strip 35 extending outwardly at right angles to the side sections at the juncture thereof. The body portion may suitably be formed by joining two angle irons as shown in Fig. 5 or it may, for example, be formed from a single sheet of material folded along its median line to form the center strip 35 and then folded to form the side sections 33 and 34. Arms 36, which are provided with flanged ends 38, are secured to the center strip 35 and extend outwardly therefrom. While three arms are shown in Fig. 5, additional arms may be provided depending upon the length of the body portion. The arms are adapted to extend into the expansion joint and to be buried in the sealing composition, thereby holding the side sections 33 and 34 against the face of the expansion joint.

The expansion joint covering device of the invention is suitably constructed of relatively flexible sheet material such as sheet steel of say 24 to 26 gauge. Thus the embodiment illustrated in Figs. 1 and 2 may be stamped or cut as a single piece from a sheet of material with the body, leg and arm portions in coplanar relationship. As thus formed the device can be conveniently accumulated in uniform stacks and packaged. The arms are flexible and they are easily bent to the desired angle and the flanged ends formed to accommodate the particular joint with which they are to be used.

Referring particularly to Fig. 3 and Fig. 4, the device of the invention is shown covering the vertical faces of expansion joints, constructed in the usual manner, in a series of concrete steps 39 as are found for example, in a stadium terrace. In using my device as shown, the body of the device is placed across the vertical face of the expansion joint with the arms extending into the joint and the sealing composition 40 is then poured into the joint. While the sealing composition is being poured, it is advisable to hold the device in place by means of a sheet of sponge rubber or the like which also temporarily covers any irregularities in the concrete adjacent the expansion joint and thus prevents the hot liquid sealing composition from leaking around the body of the device. The sealing composition, particularly if one of the rubberized bituminous type is used, solidifies rapidly and the arm portions of the device are soon securely held in place. The leg 11 extending downwardly into the subjacent joint is likewise buried when the sealing composition is poured into that joint and the device is thus firmly held in place. The exposed body portion may suitably be coated with an asphalt paint or similar black coating material to simulate the color of the sealing composition and thereby to conceal the presence of the metal.

Referring particularly to Fig. 6 and Fig. 7, a wall construction is shown having an expansion joint which has been covered by a plurality of superposed devices of the form illustrated in Fig. 5. In preparing such a joint the sealing

composition is preferably poured intermittently in a series of applications in order to prevent unduly large hydrostatic pressure. For example, the device is inserted into the joint at the lowermost portion thereof and sealing composition 40 is poured into the joint up to the level of the top of the device and is then allowed to solidify. Another joint covering device is then placed above the lowermost one and the sealing composition poured to the level of the top of this device and allowed to solidify. The remainder of the joint is filled in a similar manner.

It will be apparent that various modifications in the structure of the joint covering device illustrated may be made without departing from the scope of the invention as defined in the appended claims and it is therefore intended that all matter contained in the foregoing description and in the drawing shall be interpreted as illustrative and not in a limiting sense.

I claim:

1. A masonry structure comprising a pair of horizontally spaced, adjacent stepped sections, each section having upper and lower substantially horizontal faces connected by a substantially vertical face, the upper, lower and vertical faces of a section being substantially coplanar with the respective faces of the other section, an elastic sealing composition disposed in the space between the pair of sections, said sealing composition having upper and lower substantially horizontal surfaces connected by a substantially vertical surface, said upper, lower and vertical surfaces of the sealing composition being substantially coplanar with the respective faces of the pair of stepped sections, a covering device having a substantially vertical body portion overlying the vertical surface of the sealing composition and partially overlapping the vertical faces of the pair of sections to prevent lateral displacement of said sealing composition, said covering device including a lower portion of less width than said body portion, said lower portion extending downwardly from said body portion and embedded in the sealing composition between the lower horizontal faces of the pair of sections, said body portion further including a flexible arm adjacent the upper end thereof, the main portion of said arm being disposed as substantially right angles to the plane of the body portion and extending into and being embedded in the sealing composition, the free end of said arm being disposed as a substantially right angle to the main portion of said arm.

2. A masonry structure comprising a pair of horizontally spaced, adjacent stepped sections, each section having upper and lower substantially horizontal faces connected by a substantially vertical face, the upper, lower and vertical faces of a section being substantially coplanar with the respective faces of the other section, an elastic sealing composition disposed in the space between the pair of sections, said sealing composition having upper and lower substantially horizontal surfaces connected by a substantially vertical surface, said upper, lower and vertical surfaces of the sealing composition being substantially coplanar with the respective faces of the pair of stepped sections, a covering device having a substantially vertical body portion overlying the vertical surface of the sealing composition and partially overlapping the vertical faces of the pair of sections to prevent lateral displacement of said sealing composition, said body portion

including a flexible arm adjacent the upper end thereof, the main portion of said arm being disposed as substantially right angles to the plane of the body portion and extending into and being embedded in the sealing composition, the free end of said arm being disposed at a substantially right angle to the main portion of said arm.

3. A masonry structure comprising steps, a plurality of expansion joints in said steps dividing said steps into a plurality of horizontally spaced sections, each expansion joint containing an elastic sealing composition having horizontal and vertical portions, and covering devices for the vertical portions of said expansion joints, each covering device comprising a substantially flat body member positioned over a respective vertical portion of an expansion joint and partly overlying the surfaces of the adjacent masonry sections, and each body member having an elongated arm adjacent one end thereof, said arm

5

20

extending inwardly into the elastic sealing composition at a substantially right angle to the body member.
